Patented Dec. 19, 1916.

A. RAPPENECKER.

SIGNALING DEVICE FOR WRITING OR COPYING TELEGRAPHS.
APPLICATION FILED OCT. 27, 1913.

UNITED STATES PATENT OFFICE.

ALPHONS RAPPENECKER, OF BREMEN, GERMANY, ASSIGNOR TO TELEPANTOGRAPH-
GESELLSCHAFT MIT BESCHRÄNKTER HAFTUNG, OF BREMEN, GERMANY, A COR-
PORATION OF GERMANY.

SIGNALING DEVICE FOR WRITING OR COPYING TELEGRAPHS.

1,209,832.

Specification of Letters Patent. Patented Dec. 19, 1916.

Application filed October 27, 1913. Serial No. 797,686.

To all whom it may concern:

Be it known that I, ALPHONS RAPPENECKER, director, a subject of the German Emperor, residing at Rolandhaus, Am 5 Brill 8-12, Bremen, Germany, have invented certain new and useful Improvements in Signaling Devices for Writing or Copying Telegraphs; and I do hereby declare the following to be a full, clear, and exact description of the invention, such as will enable others skilled in the art to which it appertains to make and use the same.

Telegraphs which bring about the reproduction of handwriting and the like by a 15 photographic process, require, for producing a light point which leaves marks on a sensitive paper by means of two mirrors each secured to an electromagnetic rotary system, a source of light consisting of an 20 electric lamp. At the transmitter station, it is not known when writing, whether the said source of light is working. It is true that it is well known to use separate conductors for such control purposes, but the said 25 conductors in most cases, cannot be laid, or are too expensive.

This invention enables the said control to be exercised without separate conductors, in' a simple and ingenious manner.

30 It chiefly consists in making the switching in of one of the mirror systems at the receiver, dependent on the burning of the lamp, in such a manner that when the two systems of mirrors receive current through 35 a relay when the lamp is burning, a signal flag or the like appears at the transmitter, otherwise it does not appear.

The switching device is illustrated by way 40 of example in the accompanying drawing in which—

A is a transmitter and B the receiver.

The battery 5 is connected in the well known manner by the writing pencil, as soon as it is used for writing, through contacts 45 2, 3 and conductors 14, 15, to the two writing resistances 6, 7, from which the variable current for operating the writing systems 16, 17 is taken at 8, 9 to the receiver. It is necessary to have two circuits E—10 and 50 E—11 transmitting the writing currents to the receiver but the particular arrangement of connections at 6, 7, 8, 9, may be varied. The switching in of the battery current at 2, 3, can also be effected in some other manner.

When the current has been switched in at 55 2, 3, a battery current will flow from 7, 9, through the resistance 13, conductor 10, mirror system 16, conductor 38, relay 19, conductor 48, earth E, resistance 44, conductor 14, thus energizing the relay 19. The said relay 19 will attract its armature 23 and thus connect the holding relay 25 which is in series with the lamp 32, to the source of current 46. The holding relay keeps the contact 26 closed and operates a preparatory contact 65 27 for the motor 28, and also connects the system of mirrors 17 through the switch 22 to the relay 19 or to E. The relay 19 remains energized as long as the contact at 23 remains closed. After the holder relay has 70 operated the contact at 22, a current will flow from the resistance 6 through 8, signal 12, conductor 11, system of mirrors 17, conductors 22, 21, relay 19 and E, back to the battery 5. The signal 12 then appears, and 75 the writing can begin.

If the pencil is put out of use, that is to say, contact broken at 2, 3, the armature 23 falls off from the relay 19 and connects the electric motor 28 through the electromagnet 80 24, closed contact 27 on the one hand, and mechanical contact 29, and relay contact 26, on the other hand, to the battery 46. The motor 28 brings about the advance of the 85 paper band 18 together with the development and other work well known in apparatus of this kind. When the work is completed a mechanical device not shown in the drawing, breaks the contact 29 for a short time, and cuts off current from the holder 90 relay 25 which drops its armature, whereby the motor 28 is switched out. The signal 12 disappears when the pencil 1 is put out of use. This process takes place when there are no disturbances. If however the lamp 95 32 is not burning, the holder relay 25 cannot attract its armatures, and consequently cannot switch in the mirror system 17 at 22. The consequence is that the signal 12 does not appear, thus showing that the lamp 32 100 is not burning. The control is thus obtained indicating at the transmitter whether the receiver is properly working.

If the pencil is used again before the work of the motor 28 is finished, disturbances can 105 take place, for the relay 19 would be again energized and switch out the motor 28. To avoid this, an electromagnet 24 is associated

with the relay 19, which electro-magnet is connected in series through the contact 27 to the motor 28 and holds fast the armature 23 owing to its stronger power compared to 5 the winding 19, so that the armature 23 cannot be attracted by the relay 19. At the same time, the said magnet 24 breaks at 47 the joint return E, so that no current can flow from the transmitter to the receiver. 10 In that way, when the current is prematurely switched in at 2, 3, the signal does not appear showing that the work of the motor 28 is not yet finished. The armature 23 can be operated by the relay 19 only when 15 current no longer flows through the motor 28 and the electromagnet 24. The connection diagram further shows in dotted lines the well known shutting off of the lamp 32 when the pencil is pressed on and lifted off 20 from the paper. In that way, the contact 2, 4, at the pencil 1 is closed or opened, and switches in or out an alternator 40, 41. The alternating current generated is supplied to the conductor E (earth) and to the conductors 10, 11, through condensers 42, 43, passes at the receiver B through the conductor 35, condensers 36, 37 and conductor E to the electromagnet 34 which operates a shutter 33 for shutting off the lamp 32. If 25 characters are written at the transmitter, the electromagnet 34 will pull the shutter 33 away from the lamp 32, or conversely. The shutting off electromagnet 34 can also be operated through a fourth conductor by means 30 of a battery current. In such case a fourth conductor is connected at 4, and connected to 34 at 45, while the current generator 40, 41, condensers 42, 43, 36, 37 with the conductors are done away with. 35 40 13 is an equalizing resistance. 44 is used for choking the alternating current from 40, 41 going toward the resistances 6, 7. The relay 19 also has a similar effect.

What I claim as my invention and desire 45 to secure by Letters Patent is:—

1. In a writing or copying telegraph of the kind in which a spot of light from an electric lamp connected in an electric circuit at the receiving end follows the movements 50 of the transmitting pencil, the combination with one of the conductors of the electric circuit used for transmitting the writing currents, of a signal device at the transmitter end and means operated by the cur-

rent in the lamp circuit at the receiving end 55 whereby a gap in the circuit containing the signal is closed when the lamp is lighted and opened when it is not giving light.

2. In a writing or copying telegraph of the kind in which a spot of light from an electric lamp at the receiving end follows the movements of the transmitting pencil, the combination of transmitting conductors for the writing currents, a common return, a relay in series with said return, a holding 60 relay in series with the lamp at the receiving end, means operated by the relay for closing a gap in the circuit of the holding relay, a signal device at the transmitter end in circuit with one of the writing current 65 transmitting conductors and means controlled by the holding relay for closing a gap in the circuit of such transmitting conductor.

3. In a writing or copying telegraph of 70 the kind in which a spot of light from an electric lamp at the receiving end follows the movements of the transmitting pencil, the combination of transmitting conductors for the writing-currents, a common return, 75 a relay in series with said return, a switch in the circuit of said relay and return, a signal device at the transmitter end in circuit with one of the writing-current transmitting conductors, a record strip or band at 80 the receiving end, an electric motor for driving such strip, and electro-magnetic means in circuit with the motor for holding open the switch in the return circuit while 85 current is flowing to the motor thereby giving an indication through the signal at the transmitting end that the apparatus at the receiving end is not in condition for use. 90

4. In a copying or writing telegraph, the combination with the sending and receiving 95 stations, and an electric lamp at the receiving station for effecting a record of the movements of the transmitting pencil, of a signal at the transmitting station controlled by said lamp to indicate whether or not said 100 lamp is lighted.

In testimony whereof I have affixed my signature, in presence of two witnesses.

ALPHONS RAPPENECKER.
